ENGINE HEAD REMOVING TOOL

Andrew Kerzak, Bronx, N. Y.

Application December 11, 1942, Serial No. 468,639

2 Claims. (Cl. 29—84)

This invention concerns a tool for removing an engine head from an engine body or block.

The abutting surfaces of an engine head and of an engine body, aside from being drawn into tight abutment by bolts and nuts, are usually sealed by gaskets, pastes, and liquids, or combinations thereof, which are to provide a tight bond.

In addition these faces are exposed to heat, and ordinarily parts of the cooling jacket open therethrough for passage of water, so that rust and corrosion set in, all of which serve to effect or to enhance a tight freezing of the engine head onto the engine body. Such a bond offers obstacles in the removal of the engine head from the engine body, and quite often an engine is harmed and impaired by the rough treatment necessary to pry and lift the engine head off the engine body. For that reason tools have been developed which are to facilitate the removal of an engine head. They are designed upon the principle of prying or pulling the engine head loose from the engine body. On the other hand it is known that bonding materials and the abutting metals, more particularly when they have been dried and oxidized by heat and again corroded by the influx of water and the acids of the exhaust gases, cannot be pulled apart, but that the sticking surfaces part much easier if the bond is loosened and broken by tapping and knocking and then the head is pulled off.

A tool facilitating the removal of an engine head from an engine body, in the said fashion, is the principal object of the instant invention.

Other objects of this invention will be learned from the following description thereof, which is given by way of two specific embodiments. Details of those embodiments are however rendered herein for purposes of illustration only, and not in limitation of the invention.

In the drawing:

Fig. 1 shows a partly cross-sectioned elevation of a tool of this invention, as applied for the removal of an engine head, the engine head having just been lifted off the engine body.

Figs. 2 and 3 show a bisected top view and a partly sectioned elevation, respectively, of a modified embodiment of this invention.

Similar numerals refer to similar parts throughout the various views.

Fig. 1 shows the engine head or top 5 to be retained by bolt 15 in a slightly raised position above the engine body or block 4. The cooling water manifold 6 of the head 5 customarily communicates with the jacket of the engine body 4

by way of perforations 8. These perforations 8 extend through the marginal surfaces 7 of the engine head 5 and engine body 4, at which surfaces 7 the head and body are in sealed abutment when assembled.

An engine head is normally provided with a plurality of tapped holes serving for connection to the inside of the engine, some of those tapped holes overlying solid top surfaces of the engine body 4. Fig. 1 shows an adaptor 9 to be provided with the threaded shank 10 and to be secured thereby in such a tapped hole 11 of the engine head 5, that tapped hole serving normally, for instance, to receive a spark plug. If a device for this invention is however to be applied to differently tapped holes, or to the differently tapped spark plug openings of the engine head of another type of an engine, another threaded shank 12 may extend in the opposite direction on adaptor 13, such shank 12 fitting such a differently tapped hole, and the adaptor 13 being used in that case in an upside down position. A polygonal shoulder 13 facilitates engagement of the adaptor 15 by a wrench for purposes of seating it tightly in such a tapped hole in an engine head.

A thread extends through the bore of the adaptor 13 and accommodates the threaded portion 14 of a bolt 15. Bolt 15 has been rotated by manipulation of the arms or handle bars 17 which fixedly extend from a knob 18 formed on the bolt 15. One or more bolts 15 have thus lifted the engine head 5 into the raised position shown, the tip 16 at the bottom of bolt 15 resting in reaction upon a top surface of the engine body 4.

Bolt 15 has a head 19 at its upper end, which is shown to be removably attached by being screwed onto the threaded upper end 20 of bolt 15 in order to permit the weight 21 to be slipped onto the bolt 15.

Weight 21 is shaped for handling a toroidal surface 22 being indicated for such purpose.

When one or more tools of the type just described are applied to an engine head for purposes of its removal from the engine body, the bolts 15 are first raised, i. e. threaded up in the respective adaptors 13. Thus these adaptors can be inserted in the engine head 5 and secured therein, before the tip 16 of the bolt 15 touches the engine body 4. The weight 21 will of course not be in the raised position shown in the drawing, but will rest upon the knob 18 of the handle; these parts may then be engaged by the hands of the operator and he may jerk or throw the weight up against the head 19 on bolt 15 in a

tapping or knocking operation, which serves to break the bond at the sealed, abutting surfaces 7 of the engine head 5 in engine body 4. Such tapping or knocking may be repeated after the operator has screwed the bolt 15 down by manipulation of handle 17 and the engine head is thereby placed under tension relatively the engine body 4, as the tip 16 of bolt 15 starts to rotate in abutment upon the top of engine head 4. If the seal is still not broken the engine head does not readily lift off the engine body, weight 21 may again be used for tapping or knocking operation, being forced up or down and yielding blows against the head 19 or the knob 18, which are transmitted to the engine head 5 for the purpose of loosening the bond at the surfaces 7. After the engine head has then been lifted off the engine body 4 by further rotation of the bolts, the tools may be removed by unthreading the adaptors 13.

The device of this invention may be simplified and the weight of the handle portion may be effectively added to that of the weight 21 if the handle bars or arms 17 are directly applied to the weight, and the weight is rendered non-rotatable though it remains reciprocatable on the bolt, e. g. by a feather-key engaging it upon bolts 15. A modification embodying this principle is indicated in Figs. 2 and 3.

In a device of Figs. 2 and 3 the manipulating means, e. g. bars or arms 17, extend radially out from the upper end of the weight 30. By means of a square hole weight 30 reciprocatably fits the square shoulder 31 extending between the fixed head 32 and the acme thread 33 of the shoulder screw 34 of that embodiment. Acme thread 33 engages in the correspondingly tapped hole of an adaptor 35.

The outside diameter of acme thread 33 is substantially the same or less than the width across flats of the shoulder 31 so that the weight 30 may be slide onto the screw 34 from the bottom end thereof before the screw is threaded into an adaptor 35.

A device of Figs. 2 and 3 is applied to and removed from an engine head in exactly the manner hereabove described in connection with the

embodiment of Fig. 1. During the operation of removing the engine head from the engine body the element 13 may be used alternatively or simultaneously for knocking or tapping as well as for pulling the engine head from the engine body by screw action.

Having thus described my invention in detail, yet I do not wish to be limited thereby, except as the state of the art and the appended claims 10 may require, for it is obvious that various modifications and changes may be made in the form of embodiment of my invention, without departing from the spirit and scope thereof.

What I claim is:

1. A tool for removing an engine head from the engine body comprising a screw, a head on one end of said screw, an adaptor to be mounted in an opening of an engine head and threadedly accommodating the other end of said screw so that said screw may be turned in reaction against an engine body underlying the engine head on which said adaptor is mounted, a weight longitudinally slidably but non-rotatively accommodated on the first mentioned end of said screw for reaction against said head, said weight and screw having cooperating means for preventing rotation of the weight on the screw, and handle means on said weight for sliding said weight along said screw and for rotating said weight in said adaptor.

2. A tool for removing an engine head from the engine body comprising a screw having one end portion threaded, a head at the other end of said screw, the portion of the screw between said head and the threaded portion being rectangular in cross section, a weight slidably accommodated upon the squared portion of said screw and having its bore conforming to the cross section thereof to cause turning of the screw with the weight, 35 handling means carried by said weight for sliding the weight along the screw and imparting turning motion to the weight and the screw, and an adaptor threadedly accommodating the threaded portion of said screw and adapted to be 40 affixed to an engine head.
